United States Patent Office

Des. 197,221
Patented Dec. 31, 1963

197,221

OUTDOOR TELEPHONE ENCLOSURE UNIT

Henry Dreyfuss, South Pasadena, Calif., assignor to Bell Telephone Laboratories, Incorporated, New York, N.Y., a corporation of New York

Filed Nov. 13, 1962, Ser. No. 72,451

Term of patent 14 years

(Cl. D13—1)

FIG. 1

FIG. 2

FIG. 3

FIG. 1 is a perspective view of an outdoor telephone enclosure unit showing my new design;

FIG. 2 is a side elevational view of the outdoor telephone enclosure unit shown in FIG. 1; and

FIG. 3 is a fragmentary rear elevational view of the outdoor telephone enclosure unit shown in FIG. 1.

The broken lines shown in FIG. 1 are for illustrative purposes only.

I claim:

The ornamental design for an outdoor telephone enclosure unit, as shown and described.
